UNITED STATES PATENT OFFICE.

JOHN FLINDALL, OF CHICAGO, ILLINOIS.

FOOT-REST.

972,073.

Specification of Letters Patent.

Patented Oct. 4, 1910.

Application filed August 18, 1908, Serial No. 449,085. Renewed April 6, 1910. Serial No. 553,844.

To all whom it may concern:

Be it known that I, JOHN FLINDALL, a citizen of the United States, residing at Chicago, in the county of Cook and State of Illinois, have invented certain new and useful Improvements in Foot-Rests; and I do hereby declare the following to be a full, clear, and exact description of the invention, such as will enable others skilled in the art 10 to which it appertains to make and use the same.

This invention relates to foot rests for furniture such as chairs, couches and the like, and has for an object to provide an 15 improved rest adjustable relative to the article of furniture, and improved means whereby the cover is maintained in a taut position irrespective of the position of the rest.

A further object of the invention is to provide in an article of furniture means whereby the fabric forming the cover of the main 20 part of the furniture extends over and forms the cover of the foot rest without fracture, and with improved means for maintaining 25 the cover upon both the body and the foot rest in taut condition.

With these and other objects in view, the 30 invention comprises certain novel constructions, combinations and arrangements of parts, as will be hereinafter fully described and claimed.

In the drawings:—Figure 1 is a longitudinal view of one end of an article of furniture with the foot rest attached, shown with 35 the sides removed and certain parts in section. Fig. 2 is an inverted plan view of the device as seen on arrow 2 of Fig. 1. Fig. 3 is a detail view of the sliding member of the 40 foot rest with the spring adapted to hold the same in taut condition as seen from above with the cover removed.

Like characters of reference designate corresponding parts throughout the several 45 views.

The present invention is applicable to any furniture upon which a foot rest would be desirable and here shown as a chair, couch or the like, having a leg 10 supported upon a caster 11 and with cross pieces 12 supporting springs 13. Above the springs 13 a filling or stuffing 14 is employed secured at the 50 end to a cross piece 15 disposed in a horizontal position and secured to a brace or cleat 16.

Upon the legs is hinged a frame 17 the 55 sides of which are provided with outwardly

extending flanges 18 and the same is movable upon the pivot 19 and maintained in adjustment by means of the rack bar 20 engaging upon the pins 21 or in any approved 60 manner. Upon the top of the frame 17 a board 22 is mounted having clips 23 engaging beneath the flanges 18 so that the board 22 is slidable upon the frame 17.

Upon the board 22 a stuffing or filling 24 65 is employed and the cover 25 of the article is brought over the end of the stuffing 14 and downwardly over the stuffing 24 and secured as at 26 to the lower edge of the board 22. A stuffing 27 is preferably inserted between 70 the stuffing 14 and the cover 25, and the cover 25 is held taut upon the body by means of a strip of material 28 sewed or otherwise secured to the cover 25 as at 29 and with its opposite edge nailed or otherwise secured to 75 the cross piece 15 as at 30.

To maintain the cover upon the foot rest always in taut condition a U-shaped spring 31 is secured to the board 22 at one of its 80 extremities as 32 while its opposite extremity 33 is secured to the cross piece 15. As the foot rest is raised and lowered the board 22 will move slidably up on the frame 17 against the tension of the spring 31 and downwardly upon the frame under the ac- 85 tion of such spring.

What I claim is:—

1. In an article of furniture, a spring seat, an adjustable foot rest hinged to the article and embodying a slidable portion, a fabric 90 covering the seat and unbrokenly continuing to cover the foot rest and secured at its edge to the slidable portion, a strip of material secured to the article and to the fabric and adapted to hold the seat portion of the fabric 95 in position, and means carried by the foot rest adapted to act upon the slidable portion and maintain the fabric taut.

2. In an article of furniture, a spring seat, an adjustable foot rest hinged to the article 100 and embodying a slidable portion, a fabric covering for the seat unbrokenly continuing to cover the foot rest and having its edge secured to the slidable portion, a strip of material secured to the article and to the fabric adjacent the edge of the article and adapted to hold the seat portion of the fabric 105 in position, and means carried by the foot rest adapted to exert tension upon the slid- able portion and maintain the fabric taut. 110

3. In an article of furniture, a spring seat, an adjustable foot rest hinged to the article

and embodying a slidable portion, a fabric covering the seat and unbrokenly continuing to cover the foot rest and secured at its edge to the slidable portion, a strip of material 5 secured to the article and to the fabric adjacent the edge of the article and adapted to hold the seat portion of the fabric in position, and a U-shaped spring exerting ten-

sion upon the slidable portion and adapted to maintain the fabric taut.

In testimony whereof I affix my signature in presence of two witnesses.

JOHN FLINDALL.
